GOLF CLUB HEAD

George W. Behrendt, Chicago, Ill., assignor to Wilson
Athletic Goods Mfg. Co., Inc., River Grove, Ill., a corporation of Delaware

Filed Sept. 9, 1963, Ser. No. 76,524

Term of patent 14 years

(Cl. D34—5)

FIG. 1 is a front elevational view of a golf club head embodying my new design;

FIG. 2 is an end elevational view thereof;

FIG. 3 is a rear elevational view of same; and

FIG. 4 is a cross sectional view taken on the line 4—4 in FIG. 3; and

FIG. 5 is a cross sectional view taken on the line 5—5 in FIG. 3.

I claim:

The ornamental design for a golf club head, substantially as shown.
